UNITED STATES PATENT OFFICE.

BERTHA R. BURG, OF SAN DIEGO, CALIFORNIA.

GARBAGE INCINERATOR.

1,160,256.

Specification of Letters Patent. Patented Nov. 16, 1915.

Application filed May 14, 1913. Serial No. 767,595.

To all whom it may concern:

Be it known that I, BERTHA R. BURG, a citizen of the United States, residing at San Diego, in the county of San Diego, 5 State of California, have invented certain new and useful Improvements in Garbage-Incinerators; and I do hereby declare the following to be a full, clear, and exact description of the invention, such as will 10 enable others skilled in the art to which it appertains to make and use the same.

This invention relates to garbage incinerators.

The object of the invention resides in the 15 provision of a garbage incinerator which will efficiently consume garbage placed therein in a relatively short period of time.

A further object of the invention resides in the provision of a garbage incinerator 20 which may be located conveniently for constant use without giving forth offensive odors, and which will be simple in construction and cheap to manufacture.

With the above and other objects in view 25 the invention consists in the details of construction and in the arrangement and combination of parts to be hereinafter more fully described and particularly pointed out in the appended claim.

30 In describing the invention in detail reference will be had to the accompanying drawings wherein like characters of reference denote corresponding parts in the several views, and in which—

35 Figure 1 is a front elevation of a garbage incinerator constructed in accordance with the invention; Fig. 2, a vertical section of what is shown in Fig. 1; Fig. 3, a section on the line 3—3 of Fig. 2; Fig. 4, a detail perspective view of the cage, and Fig. 5, a partial vertical section showing the smoke pipe telescoped.

40 Referring to the drawing the garbage incinerator is shown as comprising a casing 10 supported upon legs 11. The upper end of the casing 10 is open and adapted to be closed through the medium of a suitable removable cover 12. Mounted in the casing 10 above the lower end thereof is a grate 13 beneath which is slidably arranged an ash pan 14. Constructed in the casing 10 between the ash pan 14 and grate 13 is a door 15 whereby a fire may be lighted upon the grate 13 and a suitable draft supplied 45 to said fire subsequent to the lighting thereof. The side walls of the casing 10 have

mounted thereon an inwardly directed plate 16. This plate 16 is provided with perforations 17 for a purpose that will presently appear. Supported upon the plate 16 within the casing 10 is a basket 18, shown in this instance as constructed of wire mesh, but it will be obvious that said basket can be constructed of any desirable perforated material. The upper edge of the basket is provided with a laterally directed strengthening frame 19 which is engaged upon the upper side of the plate 16 and serves to support the basket 18 in suspension within the casing 10. One of the side walls of the casing 10 is provided with an opening 21 mounted upon this side wall and communicating with the opening 21 is a telescoping stove pipe 22 which in the collapsed position thereof is adapted to be closed by a 75 cap 23.

In the use of the incinerator fuel is first placed upon the grate 13 through the open upper end of the casing 10. The basket 18 is then applied as shown in Fig. 2 and the 80 garbage to be burned is placed within the said basket. The pipe 22 is then extended to the position shown in Fig. 2 and the cover 12 applied. The fuel upon the grate 13 is then ignited through the door 15. As 85 the fuel burns the heat will rise and pass through the openings 17 with the result that the garbage in the basket 18 is soon dried to a state in which it will be ignited and burned. Owing to the openings 17 it will 90 be apparent that the draft during the preliminary burning of the garbage is in no way interfered with so that an efficient fire is maintained for reducing garbage to a dry and burnable state. It will be further 95 apparent that if the door 15 is left open and the garbage deposited at intervals in the basket 18 a circulation of air will be maintained so as to dry out the garbage previous to the burning. The device is adapted to 100 also be used as a heater and cooker and to this end there is detachably mounted in the casing 10 above the plate 16 a plate 24 provided with a plurality of openings 25 closed by removable lids 26. When the device is 105 used as a heater and cooker the material to be heated and cooked is simply placed upon the plate 24, the cover 12 having been previously removed.

What I claim is:—

110 A garbage incinerator comprising a casing having an open upper end, a pyramidal

removable cover for closing the upper end of said casing, a grate disposed in said casing, means for supplying draft to fuel disposed upon the grate, a garbage supporting receptacle removably suspended in the casing above the grate, a plate removably supported in the casing above the receptacle and beneath the upper end of the casing and forming a storing space between the

plate and cover, and a smoke pipe leading 10 from the casing between the upper end of the garbage receptacle and said plate.

In testimony whereof, I affix my signature, in the presence of two witnesses:

BERTHA R. BURG.
